UNITED STATES PATENT OFFICE.

WILLIAM O. STEPHENSON, OF CINCINNATI, OHIO, ASSIGNOR TO M. M. BUCK,
OF ST. LOUIS, MISSOURI.

RAILWAY-LANTERN.

SPECIFICATION forming part of Letters Patent No. 256,402, dated April 11, 1882.

Application filed February 7, 1882. (No model.)

To all whom it may concern:

Be it known that I, WILLIAM O. STEPHENSON, of Cincinnati, Hamilton county, Ohio, have invented a new and useful Improvement 5 in Railway-Lanterns, of which the following is a specification.

My invention relates to a provision within or beneath the base of a railway lamp or lantern of a holder or receptacle for torpedoes.

10 It is well known to be among the most important of the onerous and responsible duties of train-officers to give warning to approaching trains of any discovered obstruction or impediment by depositing torpedoes upon a portion of the track which the engine of the expected train will traverse. It too often happens, in the hurry and excitement of the occasion, where every moment is of importance, that torpedoes cannot be found; and it is to 15 insure the possession by the trackmen or brakemen of a supply of torpedoes instantly accessible at the critical moment that the present improvement has been devised.

20 In the accompanying drawings, Figure 1 is a side elevation of a railway lamp or lantern provided with one form of my improvement, a portion of the base or foot being shown broken away so as to lay bare the torpedo-receptacle. Fig. 2 is a vertical section through the receptacle and a portion of the base. Fig. 3 is a horizontal section through the receptacle. Fig. 4 is a perspective under side view of the receptacle with the contiguous parts of the lantern-bottom, the cap being represented detached. Figs. 5 and 6 are respectively a side elevation and a perspective view of a modification of my improvement. Figs. 7 and 8 are 25 respectively a side elevation and a vertical section of another modification.

20 A may represent a railway lamp or lantern having customary inverted saucer-formed base or foot, B, extending downward and outward from the floor or bottom C. Projecting downward from the under side of said floor is a cylindrical chamber, D, which constitutes the body of the receptacle. The depth and interior diameter of said receptacle are such as to 45 easily contain the desired number (say two) of torpedoes E.

The torpedoes are retained within said receptacle by means of a cap, F, in whose bayonet-notches engage studs d, that project from the receptacle-body. A spring-catch, G, by snapping over one of the studs d, prevents the possibility of accidental separation of the 50 cap.

A helical spring, H, fastened at one end to the floor C and depending therefrom within the receptacle-body, presses upon the topmost torpedo and prevents the torpedoes rattling or 55 slipping about within the receptacle.

When the torpedoes are wanted the operator has only to open the spring-catch G and withdraw the cap, which latter then brings the torpedoes away with it in convenient position for conveying to the desired spot upon the track.

In Figs. 5 and 6 is seen a modification of my improvement, in which the receptacle P is hinged, as at p, to a corresponding shallow 70 curb, Q, and is fastened shut by means of a spring-catch, R, that engages over a stud, r, upon the said hinged receptacle. A spring, H, of identical form with that in the form first described, operates in like manner.

75 Figs. 7 and 8 represent still another modification, that consists of a metallic diaphragm, I, which, in conjunction with the flaring base and with the floor, constitutes the receptacle. Access to this form of receptacle is afforded 80 by apertures J, which are closable by sliding shutters K, that are capable of being fastened by means of catches L. In this form the rattling of the contents is prevented by thumb-screw and nut M N, the screw M of which, 85 being secured to the lantern-floor, extends through an orifice, I, in the diaphragm. By turning the nut N to right the diaphragm I is elevated, and, pressing upon the contents, retains them in place. A contrary turn of said 90 nut leaves the torpedoes lying loosely within the receptacle, so as to be capable of being readily emptied out on withdrawal of the shutter.

An incidental advantage of my attachment 95 is the increased weight imparted to the lantern-base with consequent greater stability.

I claim as new and of my invention—

1. A railway lamp or lantern whose foot or base contains a holder or receptacle, D, a cap, F, and a spring catch or fastening, G, substantially as set forth.
- 5 2. The torpedo-holding attachment for railway-lanterns, consisting of receptacle D, cap F, fastening G, and anti-rattling spring H, substantially as set forth.

In testimony of which invention I hereunto set my hand.

WILLIAM O. STEPHENSON.
